(57) **CLAIM**

The ornamental design for a door switch casing, as shown and described.

DESCRIPTION

FIG. 1 is a bottom perspective view of a door switch casing showing my new design;

FIG. 2 is a top perspective thereof;

FIG. 3 is a top view thereof;

FIG. 4 is a bottom view thereof;

FIG. 5 is a front view thereof;

FIG. 6 is a front view thereof;

FIG. 7 is a right view thereof;

FIG. 8 is a left view thereof;

FIG. 9 is a top perspective view of the door switch casing shown in a first environment of use; and,

FIG. 10 is a bottom perspective view thereof.

The broken lines in the drawings illustrate environmental subject matter that forms no part of the claimed design.

1 Claim, 10 Drawing Sheets
